CLAIM

We claim the ornamental design for an optical module, as shown and described.

DESCRIPTION

FIG. 1 is a front perspective view of an optical module according to the present invention.

FIG. 2 is a front elevation view of the optical module of FIG. 1.

FIG. 3 is a rear elevation view of the optical module of FIG. 1.

FIG. 4 is a top view of the optical module of FIG. 1.

FIG. 5 is a bottom view of the optical module of FIG. 1.

FIG. 6 is a right side elevation view of the optical module of FIG. 1; and,

(Continued)

FIG. 7 is a left side elevation view of the optical module of FIG. 1.

Broken lines and unshaded portions contained within broken lines illustrate elements of the optical module that form no part of the claimed design.
